UNITED STATES PATENT OFFICE.

WILLIAM T. BLOUNT, JR., OF THUNDERBOLT, GEORGIA.

SAW-HANDLE.

No. 832,529.

Specification of Letters Patent.

Patented Oct. 2, 1906.

Application filed January 16, 1906. Serial No. 296,362.

To all whom it may concern:

Be it known that I, WILLIAM T. BLOUNT, Jr., a citizen of the United States, residing at Thunderbolt, in the county of Chatham and State of Georgia, have invented new and useful Improvements in Saw-Handles, of which the following is a specification.

This invention relates to saw-handles, and has for its objects to provide a comparatively simple inexpensive device of this character which may be readily applied to the various forms of saws now in general use, one which will hold a comparatively large quantity of oil for lubricating the saw-blade, one in which the lubricant may be conveniently discharged from time to time as circumstances require, and one wherein the lubricant when discharged will be properly and equally distributed to both sides of the blade.

With these and other objects in view the invention comprises the novel features of construction and combination of parts more fully hereinafter described.

In the accompanying drawings, Figure 1 is a side elevation of a portion of a saw equipped with a handle embodying the invention. Fig. 2 is a view, partly in section, the section being taken centrally and longitudinally through the handle. Fig. 3 is a section taken at right angles to Fig. 2 on the line 3 3 of Fig. 1.

Referring to the drawings, 1 designates a saw-blade of usual form and material equipped with a handle 2, composed, preferably, of sheet metal and of hollow construction to present an oil chamber or reservoir 3, provided with an oil-inlet opening or port 4, normally closed by a screw-threaded plug 5, and with a forwardly-extending tubular discharge-port 6, conically tapered, as shown, and centrally slotted from its forward end throughout a portion of its length, as at 7, to receive the saw-blade. The handle 2 is provided at its forward end with an opening or slot 8 for the reception of the blade, the slotted portion of the handle having inner side walls or webs 9, which lie on opposite sides of the blade, and an inner web 10, joining the side walls at the end of the blade, in which is formed a recess 11 for the entrance of the discharge-tube 6. Fitted within and for normally closing the tubular discharge-ports 6 is a tapered plug-valve 12, carried by a stem 13, slidably disposed in a guide-opening 14, formed in the front wall of the hand-receiving opening 15 of the handle, there being pro-

vided on the outer end of the stem 13 a knob or head 16, adapted to be engaged for moving the valve to open position, while coiled upon the stem 13 is a compressible spring 17, serving to maintain the valve firmly seated in closed position.

In practice the chamber 3 of the handle is filled with oil introduced through the opening 4, which is thereafter closed by the plug 5. In using the saw the lubricant flows freely to the discharge-tube 6, through which it may be discharged from time to time, as required, upon the blade 1 by grasping the head 16 and momentarily opening the valve 12. It is to be observed that the head 16 may be grasped by the forefinger and thumb of the hand which holds the handle 2 and that the lubricant in passing out through the tube 6 is, owing to the latter being slotted for the reception of the blade, properly and equally distributed upon both sides of the latter.

From the foregoing it is apparent that I produce a simple device admirably adapted for the attainment of the ends in view, it being understood that in attaining these ends minor changes in the details herein set forth may be resorted to without departing from the spirit of the invention.

Having thus described my invention, what I claim is—

1. A scroll-handle for saws having its entire grip portion made hollow to provide an oil-receiving chamber and having integral continuous walls wholly impervious to liquid, thus to prevent leakage of oil from the chamber, said chamber being provided with inlet and discharge ports, a valve for closing the latter port, a spring for maintaining the valve in closed position, said valve being movable at will against the action of the spring, and a closure for the inlet-port.

2. A scroll-handle for saws having its entire grip portion of hollow formation to provide an oil-receiving chamber and formed with integral continuous walls wholly impervious to liquid, thus to prevent leakage of oil from the chamber, the latter being provided with an inlet and a discharge port, a closure for the inlet-port, a valve arranged for closing the outlet-port and provided with a stem slidable through the wall of the grip portion, and a spring arranged upon the stem for maintaining the valve in closed position.

3. A scroll-handle for saws having its entire grip portion of hollow formation to provide an oil-receiving chamber and formed

with integral, continuous walls wholly impervious to liquid, thus to prevent leakage of oil from the chamber, said handle having a blade-receiving slot and the chamber being provided with oil inlet and discharge ports of which the latter is adapted to discharge lubricant upon opposite sides of the blade, a closure for the inlet-port, a spring for main-

taining the valve in closed position, and means for opening the valve at will. 10

In testimony whereof I affix my signature in presence of two witnesses.

WILLIAM T. BLOUNT, JR.
